UNITED STATES PATENT OFFICE.

JOHN ASTROM, OF FORT WAYNE, INDIANA, ASSIGNOR TO FORT WAYNE ENGINEERING AND MANUFACTURING COMPANY, OF FORT WAYNE, INDIANA.

PUMP.

1,196,920.

Specification of Letters Patent. Patented Sept. 5, 1916.

Application filed August 20, 1915. Serial No. 46,488.

To all whom it may concern:

Be it known that I, JOHN ASTROM, a citizen of the United States, and resident of Fort Wayne, in the county of Allen and 5 State of Indiana, have invented certain new and useful Improvements in Pumps; and I do hereby declare that the following is a full, clear, and exact description thereof.

My invention has for its primary object to 10 provide a simple, economical and effective discharge valve, the same being particularly applicable to pumps of various types.

The invention generically contemplates the embodiment of complementary shell 15 members which are spaced apart to constitute a port therebetween and the opposite end faces of said shell members are arranged to form a valve seat, which valve seat is controlled by an elastic valve ring that is adjusted upon the seat under a slight tension, whereby the port is closed, opening of said 20 port being effected by radial pressure from within whereby the ring is momentarily expanded.

Hence the primary objects of my invention are to provide a discharge valve for 25 pump cylinders which is so constructed as to produce a maximum port opening with a minimum amount of motion, whereby a 30 rapid and noiseless seating of the valve is insured at a much greater pump speed than is possible with pump valves of the ordinary type; to provide a type of discharge valve which permits an arrangement whereby the 35 clearance space can be reduced to a minimum so that the pump in starting will act as an air compressor of high efficiency and will initially rid itself of any air, resulting in a 40 pump having the functions of a self primer to a much greater extent than that in pumps employing discharge valves of ordinary construction, which latter valves require considerable space for their accommodation.

Another object of my invention is to 45 reduce the necessary clearance space of suction valves to a minimum and, with this in view, I preferably employ a suction valve of the puppet type, which adds comparatively nothing to the restricted clearance space that 50 is rendered possible by my novel arrangement, but it is understood that I may, without departing from the spirit of my invention, employ any type of suction valve in conjunction with my improved discharge 55 valve embodying the shell members spaced

apart to form a port which is controlled by an elastic ring valve.

Still another object of my invention is to provide a balanced suction valve whereby it is rendered free to perform its functions, 60 such balance mechanism being so proportioned as to properly cushion the valve and also to cause it to seat at the proper time without hammer.

With the above objects in view the invention 65 consists in certain peculiarities of construction and combination of parts as fully set forth hereinafter with reference to the accompanying illustrations and subsequently claimed.

In the drawings Figure 1 represents a 70 longitudinal sectional view exemplifying a certain type of pump equipped with valve mechanism embodying my invention, the section being indicated by line 1—1 of Fig. 75 2; Fig. 2, a cross-section of the same, the section being indicated by line 2—2 of Fig. 1; Fig. 3, a detailed cross-section through the cap portion of the pump showing vent means for a suction valve, and Fig. 4, a longitudinal sectional view of another type of pump 80 embodying the features of my invention.

Referring by characters to Fig. 1 of the drawings, 1 represents a pump cylinder, 85 which pump cylinder forms part of a housing 2 having circular pockets 3, 3', at its opposite ends. The pockets communicate with the open ends of the pump cylinder 1 and are connected by flow channels 4, 4', above and below the cylinder. The pump housing at one end is formed with a suitable stuffing box 2' provided with a packing and gland cap, through which a reciprocative piston 5 extends. The piston, in this 90 exemplification of my invention, is reduced in diameter and carries an enlarged piston head 5' that is reciprocatively mounted within the cylinder 1 in the ordinary manner. The said cylinder is lined with a shell member 6 and the rear end of the same projects into 95 the pocket 3 and is flanged outwardly, which flange terminates with a beveled face 7 that forms one-half of a valve-seat. The opposite half of the valve-seat is formed by an oppositely beveled face 7' of a shell member 8, which shell member forms a cap closure for this end of the pump housing, the same being secured to the latter by suitable bolts. The opposite ends of the two shell members 100 are spaced apart, as shown, to form a re- 105

110

stricted port *a*, and this port is normally closed by an elastic ring *b*, which ring is initially tensioned to insure its firm seat upon the complementary faces of the shell members, whereby the discharge port *a* is closed. The ring, as shown, is preferably circular in cross-section, and while so shown it should be understood that other cross-sectional forms of ring may be employed, as well as other forms of seating faces for said ring, without departing from the spirit of my invention.

The shell 8 projects outwardly beyond the water pocket 3 and forms an intake chamber 9 having a threaded opening 9' therein for the reception of a fluid supply pipe, not shown. The water chamber 9 extends through the inner face of the shell 8 and said inner face is formed with a seat for a beveled valve-disk 10, which disk, when seated, is upon a common plane with the end wall of the shell member 8, which forms one side of the discharge port *a*. The valve disk 10 constitutes a suction valve for controlling fluid entering the pump cylinder and said disk is carried by a stem 11, which stem extends into a hollow hub 12 that forms part of the shell member 8. The rear end of the valve-stem 11 carries a guide washer 11' which is formed with a series of longitudinal grooves 11'' and interposed between the inner face of the washer and the base of the hollow hub, is a helical spring 13, which helical spring exerts its force to hold the suction valve to its seat.

In order to balance the suction valve whereby free motion of the same may be had, the hollow hub 12 is provided with vent holes 12' at its rear end, whereby water is permitted to enter the hollow hub and upon opposite sides of the washer 11' through the washer grooves 11'', the size of the vent holes and grooves being predeterminedly proportioned so as to properly cushion the valve and cause it to seat quickly and at the proper time without liability of hammer. It is also obvious that for the purposes of assemblage and convenience in manufacture the bore of the hollow hub 9 is open at its outer end and threaded whereby the valve parts may be properly assembled and thereafter the open threaded end is closed by a threaded plug 13'.

In this exemplification of my invention it will be observed that the pump is of the differential type with a single acting suction and a double acting discharge. Upon a suction stroke of the piston the discharge corresponds to the differential area between the piston rod and piston head and on the return stroke the discharge corresponds to the displacement of the piston-rod. It will also be manifest that by proportioning the area of the piston-rod one-half that of the piston-head, the discharge becomes equal on each

stroke. Hence upon a suction stroke the puppet-valve opens and upon the compression stroke of the piston it will close and the elastic ring will be lifted from its seat, whereby the port *a* is opened and the fluid within the cylinder between the end face of the piston head and end face of shell 8 will be discharged through said port and upon completion of the discharge stroke it will be obvious that the elasticity of the ring will quickly cause contraction of the same, whereby the discharge port is closed.

Referring to Fig. 4 of the drawings, as shown, the valve mechanism therein is identical with that described in connection with Figs. 1 to 3 inclusive and the pump structure in this instance is of the single acting type, there being no reduction in diameter of the piston-rods 5. It is also manifest that I may embody my valve mechanism in a double acting pump having a suction valve and a discharge valve as disclosed by me positioned at both ends of the cylinder, without departing from the spirit of the invention. It will also be seen that the shape of the discharge valve ring offers very little resistance to the flow of fluid and the fact that opening takes place at each seat 7, 7', renders it possible to reduce said opening to a minimum area. Furthermore the valve is very light and will therefore quickly respond and will closely follow the motion of the plunger or piston to thus seat the moment the plunger comes to rest at the end of its stroke, even though the number of strokes per unit of time be greatly increased. It is also quite evident that the clearance space created by the discharge valve is limited to the small circular ring immediately under the valve and therefore can be kept down to a small percentage of the displacement of the plunger. If, therefore, any air is present in the pump, which is often the case in starting up, or if the suction pipe should have a leak, this air will be drawn into the cylinder and there highly compressed and forced through the discharge valve even against a high pressure behind said discharge valve. The pump is thus capable of effectually eliminating air there-within which is not the case in pumps with a large clearance space for the reason that such large clearing space design allows the air to contract and expand with the motion of the plunger and prevent the pump from priming itself.

I claim:

1. The combination of a pump cylinder having alined shell members spaced apart to constitute a port therebetween, the opposite companion end faces of which shells conjointly form a valve seat, and an elastic valve ring fitted to the valve seat.

2. The combination of a pump cylinder having alined shell members spaced apart to

constitute a port therebetween, the opposite companion end faces of which shells conjointly form a valve seat, and an initially tensioned elastic valve-ring fitted to the

5 valve seat.

3. The combination of a pump cylinder having alined shell members spaced apart to constitute a port therebetween, the opposite companion end faces of which shells 10 conjointly form a valve seat, and an initially tensioned elastic valve-ring fitted to the valve seat the ring being circular in cross-section.

4. The combination of a pump cylinder 15 having alined shell members spaced apart to constitute a port therebetween, the opposite end faces of which shell members are beveled to form a valve-seat, and an elastic valve ring fitted to the valve seat, the ring being 20 circular in cross-section.

5. The combination of a pump cylinder having shell members spaced apart to constitute a port therebetween, the opposite end faces of which shell members are beveled to form a valve-seat, and an elastic valve-ring fitted to the valve-seat.

6. The combination of a pump cylinder having alined shell members spaced apart to constitute a port therebetween, the opposite 30 companion end faces of which shells conjointly form a valve seat, an elastic valve ring fitted to the valve seat, a piston fitted in one of the shell members, and a check-valve controlled port in the opposite shell member.

35 7. The combination of a pump cylinder comprising alined shell members having their inner ends spaced apart to form a valve-seating discharge port therebetween, one of said shell members being provided with an 40 intake port, an elastic ring adapted to close the discharge port, a hollow vented hub carried by the intake ported shell member, a valve for the intake port, a stem carried by the valve extending into the hollow hub, the

stem being provided with a grooved washer, 45 and a spring seated in the hollow hub engageable with the washer for holding the intake valve to its seat.

8. A pump comprising a housing having a water pocket at one end, an open ended 50 cylinder in communication with the pocket, the said cylinder constituting a sleeve member, a cap constituting a second shell member extending into the pocket opposite the first mentioned shell member, the last mentioned shell member being provided with an intake port and spaced from the first mentioned shell member to form a discharge port, an elastic ring for engaging the complementary ends of the shell members for 55 closing the discharge port, a check valve for closing the intake port, and a reciprocative piston fitted within the opposite sleeve member.

9. A pump comprising a pair of circular 65 alined shell members having juxtaposed ends, one of which shells constitutes a cylinder and the other a water intake chamber having a valve-controlled intake port in its end opposite the first mentioned shell, the 70 said juxtaposed shell ends being provided with complementary valve seating surfaces which are spaced apart to form an annular discharge port, a housing surrounding the juxtaposed shell ends forming a water 75 pocket, an elastic ring valve engageable with the valve seats formed by the shell ends, and a pump piston reciprocatively mounted in that shell member which constitutes a pump cylinder.

In testimony that I claim the foregoing I have hereunto set my hand at Fort Wayne, in the county of Allen and State of Indiana, in the presence of two witnesses.

JOHN ASTROM.
